UNITED STATES PATENT OFFICE

GEORGE FORDHAM JONES, OF PITTSTON, PENNSYLVANIA.

IMPROVEMENT IN BALING-PRESSES.

Specification forming part of Letters Patent No. 173,965, dated February 22, 1876; application filed February 14, 1876.

To all whom it may concern:

Be it known that I, GEORGE FORDHAM JONES, of Pittston, Luzerne county, Pennsylvania, have invented certain Improvements in Baling-Presses, of which the following is a specification:

My invention consists of a hay or cotton press, constructed as fully described hereafter, so as to insure greater simplicity in construction and operation, greater strength and durability, and reduce the weight.

In the accompanying drawing, Figure 1 is a side elevation, showing a portable hay-press constructed in accordance with my invention; and Fig. 2 a plan view, showing the parts in a different position.

A is the bed-plate, which may be secured firmly to a stationary foundation, but which is preferably mounted upon wheels, so as to constitute a truck. B is a casing, constructed in any suitable manner, containing the baling-chamber, and mounted on the bed-plate, so that it may be secured stationary, or so as to slide thereon to a limited extent. Upon the bed-plate, opposite the casing B, is arranged a steam-engine, C, the valve of which is controlled from the piston-rod *a* through the medium of a rod, *b*, connected at one end to an arm on the piston-rod, and at the other end to an arm, *c*, on the rocking valve-spindle *d*. To the outer end of the piston-rod is secured a plate or platen, *e*, of such a size as to readily enter the open inner end of the chest B. The flange and cap, at the rear end of the cylinder, are enlarged to form a second stationary platen, *e'*, and the engine is so connected to the bed-plate that it may be reversed to the position shown in Fig. 2, for the purpose described hereafter.

The engine is supplied with steam from a stationary or portable boiler, and operates automatically, the valve being so constructed as to reverse the piston at the end of the stroke. The hay is thrown into the inner end of the chest B, in front of the platen *e*, which, as it moves forward, compresses the hay in the chest, and then retires prior to another quantity of hay being introduced, these operations being repeated until a bale of sufficient size is formed, when it is tied and removed.

It will be seen that by combining the baling-chest B with a direct operating engine the use of cranks, jointed rod and arms, and gearing is avoided, insuring great strength and durability, and greatly reducing the weight of the apparatus.

The chief advantage, however, is in the simplicity of the construction, which is of the utmost importance in apparatus which have to be handled by farmers and others unskilled in the use of steam machinery.

By mounting the engine and baling-chest upon a truck the apparatus is rendered portable, and the necessity of employing a separate truck, heretofore required with portable baling-presses, is avoided. Although I prefer to use a stationary chest, B, and a movable platen, the chest may slide upon the platform, as before described. In this case the engine is turned to the position shown in Fig. 2, and the chest B is connected by rods *x* to the platen *e*, the hay being forced into the chest as the latter approaches the stationary platen *e'*.

It will be seen that the effect is the same in both cases, the engine acting directly to compress the hay in the baling-chamber.

Without limiting myself to the precise construction and arrangement of parts described, I do not claim the combination of a direct-acting engine, and a platen attached to the piston-rod; neither do I claim a platen reciprocating in or opposite to a baling-chest; but

I claim—

The combination of a baling-chest, B, and an engine, C, having a platen, *e*, connected to the piston-rod, and operating directly to form a bale by packing the material in small quantities at each forward movement in the baling-chamber.

In testimony whereof I have signed my name to this specification in the presence of two subscribing witnesses.

G. FORDM. JONES.
